UNITED STATES PATENT OFFICE.

CHARLES G. NELSON, OF CHICAGO HEIGHTS, ILLINOIS, ASSIGNOR TO ZOURI DRAWN METALS COMPANY, OF CHICAGO HEIGHTS, ILLINOIS, A CORPORATION OF ILLINOIS.

SELF-SUPPORTING SASH.

Application filed March 25, 1926. Serial No. 97,363.

My invention relates to devices for holding window panes, and more particularly to self supporting sashes for plate glass windows.

- 5 My invention has for its object to provide means whereby sash intended for use where window frame members are arranged so as to form a right angle between them for the reception of the sash may be readily modified to perform its function where the window frame presents only a supporting surface perpendicular to the glass. Further details of the invention will appear as the description proceeds.
- 10 15 The invention will be disclosed in connection with a sash similar to that shown and claimed in my Patent No. 1,570,702, dated January 26th, 1926, some features of the sash being modified in accordance with my 20 application on Serial No. 98,187, filed March 29, 1926.

In the accompanying drawing, forming a part of this specification, Fig. 1 is a cross-section of a sash embodying my invention; Fig. 2 is a perspective view of a stiffening bracket used in the device shown in Fig. 1; Fig. 3 is a view similar to Fig. 1 showing a modified form of my invention; Fig. 4 is a perspective view of the stiffening member shown in Fig. 3.

The sash shown is adapted to be applied to a window frame member 10 having its supporting surface perpendicular to the edge of the glass 11. The sash consists of an inner clamping member 12 and an outer clamping member 13. The inner clamping member has an upper flange 14 extending to the surface of the glass and a flange 15 on the edge of portion 14 adapted to lie against the face of pane 11. Clamping member 12 has a flange 16 on its other edge adapted to lie against supporting member 10. The front clamping member 13 has a flange 17 at its upper edge adapted to contact the face of the glass substantially opposite flange 15. At its lower edge clamping member 13 has a bead 18 adapted to rest against the surface of supporting member 10 and against the front edge of flange 16. A flange 19 extends inward from bead 18 at a slight distance above flange 16.

Within the rear clamping member 12 there is arranged a bracket member 20 similar to that disclosed and claimed in the aforesaid patent, and which need not be particularly

described in this application except that it forms a substantially box shaped member open at its front to receive the horizontal arm of an L-shaped member 21. This arm of member 21 has a cam surface 22 adapted to be contacted by a screw 23 threaded through a bushing 24 in the upper wall of bracket 20. The other arm of member 21 terminates in an end 25 adapted to fit against flange 17 and hold it against the glass. At its angle, member 21 is provided with an opening 26 adapted to receive an upturned portion 27 of flange 19 so that, when the screw 23 is driven down, it draws the outer clamping member against the glass and against supporting member 10 and flange 16.

The construction thus far described is similar to that shown in my aforesaid applications, and, therefore, is not claimed in the present application except in combination with the features hereinafter described.

The sashes in the aforesaid applications were intended for use with a riser member in position to support the rear of clamping member 12. In order to stiffen the construction so that the device may be used in the absence of such a riser, I provide a stiffening member 28 adapted to fit within bracket member 20 and hold it in proper relation to supporting member 10. The stiffening member 28 comprises a plate 29 adapted to lie upon the bottom wall of bracket 20 and having a forwardly extending portion 30 adapted to lie upon flange 16. Portion 30 is provided with a hole 31 through which a screw 32 may be driven into supporting member 10 to hold the stiffening member in place.

In the form shown in Fig. 2, flanges 33 rise from the sides of portion 29 and fit within and against the side walls of bracket 20. At the upper edges of flanges 33 there are inturned flanges 34 which fit beneath and against the upper wall of bracket 20 on the two sides of bushing 24. Preferably the parts are so arranged that the front ends of flanges 34 rest against the lower edge of flange 15.

As will be readily seen, the bracket 20 and stiffening member 28 may be readily slipped into position within the rear clamping member 12. A series of such brackets and stiffening members arranged along the length of clamping member 12 suffices to secure it in position and hold it in proper relation to

supporting member 10, a single screw 32 for each stiffening member being sufficient for this purpose. Thereafter the glass may be put in position and a front clamping member with its draw plates 21 may be thrust into proper relation with the front of the pane, and tightening screw 23 secures the front clamping member in position.

It will be readily seen from the above that

- 10 I have provided a simple stiffening member by means of which a sash such as disclosed in the above mentioned applications may be readily converted into a self supporting sash. It will be further seen that the attachment of this self supporting sash may be made very readily and with a high degree of accuracy without requiring excessive skill.

The construction shown in Fig. 3 is similar to that shown in Fig. 1 except that a different form of stiffening member is used. The stiffening member shown in Figs. 3 and 4 has a lower plate 35 with a front extension 36, similar to plate 29 and extension 30 of 25 the member shown in Fig. 2, but instead of having flanges rise from the sides of plate 35 it is provided with a flange 37 rising from the rear end of plate 35. At the top of flange 37 there is a forwardly turned flange 38 notched at 39 to fit around bushing 24. The stiffening member shown in Fig. 4 is 30 more simple and more cheaply constructed than that shown in Fig. 2, but as will be obvious must be made of stiffer material in 35 order to effect the same amount of stiffening of the sash. The member shown in Fig. 4 may be used where it is sufficient to accomplish the desired purpose, but for heavier duty the member shown in Fig. 2 is preferable.

While the terms used in the foregoing description are suitable for a construction wherein supporting member 10 is the sill beneath the pane, it will be readily understood 45 that the same sash construction may be used at the sides or top of the glass.

It will be readily understood that various changes may be made in the clamping members and in the shape and construction of 50 bracket 20 and in the arrangement of the stiffening member within the scope of the appended claims, which state what I claim as my invention.

I claim:

- 55 1. In a window sash, a rear clamping member and a front clamping member, a bracket member in interlocking engagement with the rear clamping member and having a passage-way therein transversely to the 60 plane of the glass and opening towards the front clamping member, a draw plate interlocking with the front clamping member and having an arm extending into said passage-way, means connected with said bracket 65 for drawing said arm into said passage-way,

a supporting member having a surface beyond and parallel with the edge of the glass in said sash, and a stiffening member fitting closely within said passage-way and engaging the top, bottom and side walls thereof and directly secured to said supporting member.

2. In a window sash, a rear clamping member and a front clamping member, a bracket member in interlocking engagement with the rear clamping member and having a passage-way therein opening towards the front clamping member, a draw plate interlocking with the front clamping member and having an arm extending into said passage-way, means connected with said bracket for drawing said arm into said passage-way, a supporting member having a surface beyond and parallel with the edge of the glass in said sash, and a stiffening member fitting within said passage-way with a portion thereof extending between said arm and the adjacent wall of the bracket and in front of the bracket, said rear clamping member having a flange extending forwardly beneath the forwardly extending portion of the stiffening member, and unitary means in front of the bracket for securing the rear clamping member and the stiffening member directly to said supporting member.

3. In a window sash, a rear clamping member and a front clamping member, a bracket member in interlocking engagement with the rear clamping member and having a passage-way therein opening towards the front clamping member, a draw plate interlocking with the front clamping member and having an arm extending into said passage-way, means connected with said bracket for drawing said arm into said passage-way, a supporting member having a surface beyond and parallel with the edge of the glass in said sash, and a stiffening member fitting within said passage-way and secured to said supporting member, the said stiffening member comprising a plate parallel with the surface of said supporting member and between said surface and said draw plate arm, and a flange rising from said plate and fitting against the sides and top of the passage-way of the bracket so as to hold the stiffening member in proper position within said bracket.

4. In a window sash, a rear clamping member and a front clamping member, a bracket member in interlocking engagement with the rear clamping member and having a passage-way therein opening towards the front clamping member, a draw plate interlocking with the front clamping member and having an arm extending into said passage-way, means connected with said bracket for drawing said arm into said passage-way, a supporting member having a surface beyond and parallel with the edge

- of the glass in said sash, and a stiffening member fitting within said passage-way and secured to said supporting member, the said passage-way being substantially rectangular in cross-section and the said stiffening member comprising a plate lying against the side of the passage-way nearest to said supporting member and flanges extending from the edges of said plate and fitting against the sides and top of said passage-way.
5. In a window sash, a rear clamping member and a front clamping member, a bracket member in interlocking engagement with the rear clamping member and having a passage-way therein opening towards the front clamping member, a draw plate interlocking with the front clamping member and having an arm extending into said passage-way, means connected with said bracket for drawing said arm into said passage-way, 20 a supporting member having a surface beyond and parallel with the edge of the glass in said sash, and a stiffening member fitting within said passage-way and secured to said supporting member, the said passage-way being substantially rectangular in cross-section and the said stiffening member comprising a plate lying against the side of the passage-way nearest to said supporting member and flanges extending from the 25 edges of said plate and fitting against the sides and top of said passage-way, the last said flanges fitting against a portion of the rear clamping member which contacts the 30 face of the glass.
10. In testimony whereof, I have hereunto signed my name to this specification.
15. CHARLES G. NELSON.
